DESIGN FOR A PERFUME BOTTLE AND BASE ENSEMBLE

Martin de Botelho, New York, N. Y.

Application November 18, 1933, Serial No. 49,792

Term of patent 14 years

To all whom it may concern:

Be it known that I, MARTIN DE BOTELHO, a citizen of Brazil and resident of New York, in the county of New York and State of New York, have invented a new, original, and ornamental Design for a Perfume Bottle and Base Ensemble, of which the following is a specification, reference being had to the accompanying drawing, forming part thereof.

In the drawing:

Fig. 1 is a side view of the bottle and base ensemble constituting my design;

Fig. 2 is a side view of the bottle shown in Fig. 1;

Fig. 3 is a side view of the base shown in Fig. 1;

Fig. 4 is a bottom plan view of the ensemble shown in Fig. 1.

I claim:

The ornamental design for a perfume bottle and base ensemble substantially as shown.

MARTIN DE BOTELHO.
